(57) **CLAIM**

The ornamental design for a vehicle treatment bay as shown and described.

DESCRIPTION

FIG. 1 is front perspective view of the first embodiment of a vehicle treatment bay showing our new design;

FIG. 2 is rear perspective view thereof;

FIG. 3 is front view thereof;

FIG. 4 is a rear view thereof;

FIG. 5 is a right side view thereof;

FIG. 6 is left side view thereof;

FIG. 7 is top view thereof;

FIG. 8 is a bottom view thereof;

FIG. 9 is a cross-sectional view taken along the line 9-9 in FIG. 5;

FIG. 10 is a front perspective view of the second embodiment of a vehicle treatment bay showing our new design;

FIG. 11 is rear perspective view thereof;

FIG. 12 is a front view thereof;

FIG. 13 is a rear view thereof;

FIG. 14 is a right side view thereof;

FIG. 15 is a left side view thereof;

FIG. 16 is top view thereof;

FIG. 17 is a bottom view thereof;

FIG. 18 is a cross-sectional view taken along the line 18-18 in FIG. 14;

FIG. 19 is a front perspective view of the third embodiment of a vehicle treatment bay showing our new design;

FIG. 20 is a rear perspective view thereof;

FIG. 21 is a front view thereof;

FIG. 22 is a rear view thereof;

FIG. 23 is a right side view thereof;

(Continued)

FIG. 24 is a left side view thereof;
 FIG. 25 is top view thereof;
 FIG. 26 is bottom view thereof;
 FIG. 27 is a cross-sectional view taken along the line 27-27 in FIG. 23;
 FIG. 28 is a front perspective view of the fourth embodiment of a vehicle treatment bay showing our new design;
 FIG. 29 is a rear perspective view thereof;
 FIG. 30 is front view thereof;
 FIG. 31 is a rear view thereof;
 FIG. 32 is a right side view thereof;
 FIG. 33 is left side view thereof;
 FIG. 34 is top view thereof;
 FIG. 35 is bottom thereof; and,
 FIG. 36 is a cross-sectional view taken along the line 36-36 in FIG. 32.

The evenly-spaced broken lines in the figures are for the purpose of illustrating portions of the vehicle treatment bay and form no part of the claimed design.

The dot-dashed and dot-dot-dashed broken lines are break lines. The appearance of any portion of the article between the break lines forms no part of the claimed design.
